WATER HEATER

Filed Nov. 23, 1931

Inventor:
John C. Glenn

UNITED STATES PATENT OFFICE

JOHN C. GLENN, OF CHICAGO, ILLINOIS

WATER HEATER

Application filed November 23, 1931. Serial No. 576,823.

The general object of my invention is to provide a water heater which is simple in construction and efficient in operation.

A more particular object of the invention is to provide a heater consisting of superposed conical coils with unitary means for connecting the coils in series and preventing the heating gases from passing through the space at the centers of the coils.

10 A further object of the invention is to provide a water heater composed of superposed conical coils with header means connecting the coils in series, and having therein the inlet and outlet connections for the heater.

15 Another object is to provide a heater of the class described with means for preventing the trapping of air within the coils when the heater is being filled with water.

20 Referring to the drawing, the figure shows a vertical section of my improved form of heater.

In the drawing, the heater is shown as consisting of four superposed overlapping 25 conical coils, 1, 2, 3, and 4. In the space at the center of the coils in the upper part thereof is located a header generally designated as 5.

Header 5 consists of two integral sections 30 6 and 7, section 6 being substantially horizontal and filling the central space in the upper convolution of coil 1, while section 7 is substantially vertical and extends through the central space between the coils from the lower part of section 6 to the upper convolution of coil 3. The interior of header 5 is divided by partitions 8 and 9 into inlet compartment 10, intermediate compartment 11, and outlet compartment 12.

40 Inlet compartment 10 is provided with a heater inlet opening 13 located in the rear face of the header and coil connection opening 14 located in the front face of the header and adjacent the inlet of coil 1. The intermediate compartment 11 is provided with 45 coil connecting openings 15 and 16 the latter being located adjacent the upper ends of coils 2 and 3 respectively. The outlet compartment 12 of section 6 of the header is provided with an opening 17 in its lower face for receiving the outlet of coil 4 and the

opening 18 in its upper face for connection with a delivery pipe.

Coils 1, 2, 3 and 4 are placed one above the other and are very closely spaced. The spacing is such that the convolutions of one coil are adjacent the spaces between the convolutions of an adjacent coil. This arrangement prevents stratification of the gases, making the tubes themselves act as baffles. Coils 1 and 2 are connected together at their lower ends by return bend 19, and coils 3 and 4 are connected together at their lower ends by return bend 20. The upper end of coil 1 is fitted into opening 14 of header 5 while the upper end of coil 2 is fitted into opening 15. Upper end of coil 3 is connected to the header at the opening 16. Coil 4 is provided with an extension 21 leading from the top convolution thereof to opening 17 of the header.

The operation of the device is as follows: 70 Water enters the inlet compartment of the header at opening 13, and passes through said compartment through opening 14 to the inlet of coil 1. The water passes downwardly through coil 1 and then upwardly in coil 2 to the intermediate compartment 11, and then into coil 3, in which it flows downwardly. From coil 3, the water flows into the lower part of coil 4 and thence to the outlet compartment of the header. 80

It will be noted that in my heater, the header connects with the top of each coil. This arrangement readily lends itself to the elimination of air from the coils when the heater is first filled with water as the air 85 in each coil will rise to the header compartments. In order to allow air to escape from the inlet and intermediate compartments to the heater outlet I provide small vent holes 22 in the partitions 8 and 9. 90

Various modifications may be made without departing from the invention as defined in the appended claims.

I claim:

1. In a water heater, a plurality of superposed overlapping conical coils, said coils being connected into pairs at their lower ends, each pair having an inlet and outlet, a header extending into the space in the center of said coils, partitions in said header divid-

ing its interior into a plurality of separate chambers, an inlet and outlet for each of said chambers, the inlet of one of said pairs of coils being connected to the outlet of one 5 of said chambers, the outlet of said pair being connected to the inlet of another chamber, the outlet of said last named chamber communicating with another of said pairs of coils.

2. Apparatus in accordance with claim 1 in which the outlet of the last pair of coils is connected to a chamber at the top of the header, an outlet for said chamber, and a 70 vent hole in each of the partitions for allowing air to escape from the various chambers to the heater outlet.

JOHN C. GLENN.
